PAPER FASTENER

Oscar A. Ross, New York, N. Y.

Application July 13, 1933, Serial No. 680,165

20 Claims. (Cl. 24—153)

This invention refers to paper fasteners and more particularly to that class of fasteners for clamping together a number of superimposed sheets of perforated paper such as correspond-
5 ence.

An object of this invention is to provide a fastener of this character which is of improved and economical construction and which will give highly satisfactory service in use.

10 Another object is to provide a paper fastener of comparatively low height for economizing in filing space.

Another object is to furnish novelly formed keepers for paper fasteners having sliding locks, said locks being of no greater height than other portions of the keeper.

20 Another object is to furnish novelly formed clamping members for paper fasteners which may be secured to paper folders or binders of known form without employing perforations therein other than those required for inserting the fingers of said clamping members.

Another object is to furnish novelly formed clamping members having self-perforating locking projections for securing said clamping members to paper folders or binders without employing special tools.

25 Another object is to furnish novelly formed clamping members having locking projections for locking the members to paper folders or binders, said projections being initially semi-formed for more ready packaging of said clamping members for economy in storage space, said locking projections being associated with peculiarly formed 30 openings in the clamping members for more readily assemble thereof when packaging.

Another object is to furnish clamping members for paper fasteners having initially semi-formed locking projections for locking the member to a 35 paper binder or cover the locking projection being finally formed for locking the member to said binder or cover. The operation of finally forming said locking projection acting to depress a portion of the binder or folder into an opening 40 in the member thereby minimizing the thickness of said binder or folder at the point the clamping member is secured.

Another object is to furnish a peculiarly formed locking projection for paper fastener 45 clamping members said projection having a readily bendable portion whereby in the bending thereof the main body portion thereof is not deformed.

50 Other objects and advantages will appear as 55 the description of the invention progresses, and

the novel features thereof will be pointed out in the appended claims.

In the following detailed description of the invention, reference is had to the accompanying drawing wherein several embodiments of the invention are illustrated and wherein:—

Figure 1 is a side elevational view of a clamping member for paper fasteners and Fig. 2 is a plan view of the same. Fig. 3 is a side elevational view of a modified form of clamping member, and Fig. 4 is a plan view of the same. Fig. 5 is a side elevational view of a package of clamping members, and Fig. 6 is a plan view of the same. Fig. 7 is a perspective enlarged view showing the application of the clamping member disclosed in Figs. 1 and 2, and Fig. 8 is a similar view showing the application of the clamping member disclosed in Figs. 3 and 4. Fig. 9 is a fragmental sectional view of the applied clamping member shown in Fig. 7. Fig. 10 is a super-enlarged part sectional view of a paper fastener including an improved form of keeper, and Fig. 11 is a part plan view of the same on a smaller scale.

Referring to Figs. 10 and 11, the paper fastener 1 for binding paper sheets 2 comprises keeper 3 and clamping member 4, said clamping member includes fingers 5 and may be of any of the forms shown herein.

Keeper 3 comprises keeper plate 60 having raised re-enforced end portions 6 including perforations 7, said perforations being formed by depressing the tongue or wall portion 8 downwardly as more fully described in my co-pending application Ser. No. 677,574, filed June 26, 1933, said perforation receiving clamping member 35 fingers as 5.

Connecting the end portions 6, are connection rails 9 comprising rail portions 10 and re-enforcing wall portions 11 comprising substantially "angle bars", the end portions 6 and rails 9 forming a rectangular frame having openings 12 into which clamping fingers, as 5, are bent downwardly to rest on the paper sheets 2. The bridge portion 13 of end portions 6 is depressed downwardly whereby the bend in fingers 5, is positioned at a point below the upper surface of said end portions and preferably as low as possible. The rail portions 9 are also depressed below the upper surface of end portions 6 whereby the locks 14 in their raised or locked position are substantially of the same height as the end portions 6. Locks 14 comprise shoe portions 15 having locking recesses 16 lockably engaging locking projections 17 on rail portion 10 as more fully described in my co-pending application, Ser. No. 55

643,773, filed November 21, 1932, now Patent No. 1,908,644, dated May 9, 1933. Shoe portions 15 are joined by bridge portions 18 having transverse trough portions 19 acting to engage fingers 5, also acting to produce a minimum height for the bridge portion with respect to the keeper plate 60.

Referring to Figs. 1, 2, and 7, clamping member 20 comprises base portion 21 having re-enforcing ribs 22. At each end of said base portion are joined fingers 23, said fingers being initially bent at an angle of 45° from the base portion for more readily packaging of the clamping members as shown by the full lines of Fig. 1. Locking projections or tongues 24, are formed from the base portion 21 inwardly adjacent the base of fingers 23 and are initially also formed at an angle of approximately 45° to the plane of said base portion for more ready packaging. The openings 25 in said base portion have an area greater than the area of said locking projections. This peculiar feature serves a double purpose. The increased area of the openings permits more ready assembly of a number of clamping members for packaging. The increased area of openings 25 also permits a portion of the binder or folder onto which locking projections 24 are depressed to enter said openings and lie between re-enforcing ribs 22. The locking projections 24 are provided with a groove or more readily bendable portion 28 to permit the bending thereat when the clamping member is applied to the binder or folder. The clamping member 20 when semi-formed as shown by the full lines of Figs. 1 and 2 will nest for more economical packaging as shown by the portion of the package thereof at the left of line A—A of Figs. 5 and 6.

When it is desired to attach a clamping member to a binder or folder, the fingers 23 and locking projections 24 are bent to a second semi-formed substantially vertical position as shown by the dotted forms 23a and 24a, thereafter said fingers and locking projections are inserted through a perforation, as 26, in the binder or folder 27, as shown by Fig. 7, the locking projections 24 being finally bent over the inside of said folder 27 as more fully shown by Figs. 7 and 9, the portion of said binder or folder underlying said locking projections being depressed into openings 25 thereby minimizing the thickness of said binder or folder at the point said clamping member is secured thereto. By securing clamping members to binders or folders in the manner described, they do not accidentally become detached therefrom when the folders are moved during the operation of adding or removing sheets of paper thereto and therefrom. The more readily bendable portion 28 of said locking projection acts to prevent bodily deformation of said projections as they are bent from semi-formed to final formed positions. It is to be noted that by having the fingers 23 and locking projections 24 enter the same perforation as 26, said perforations being of standard form, it is unnecessary to supply special perforations for securing said clamping members to a binder or folder.

Referring to the modified form of clamping member 30 shown by Figs. 3, 4, and 8, said member comprises base portion 31 having re-enforcing ribs 32, fingers 33, being joined to each end thereof. Said base portion also includes self-perforating locking projections 34 for perforating the binder or folder and are preferably positioned more inwardly from fingers 33 than the similar locking projections 24. Said base mem-

ber is also provided with openings 35 having an area greater than the area of said locking projections and for the same purpose as described in connection with clamping member 20. Said fingers 33 and locking projections 34 are also initially semi-formed at an acute angle to the plane of the base portion for more readily nesting as shown by the package of clamping members to the right of line A—A of Figs. 5 and 6.

When a clamping member as 30 is to be applied to a binder or folder, the fingers 33 and locking projections 34 are reformed to a second semi-formed position as shown by the dotted lines 33a and 34a, thereafter the fingers 33 are inserted through the usual perforations 26, the locking projections 34 piercing the binder or folder after which said locking projections are bent downwardly to final form, in this manner depressing a portion of the folder 27 downwardly into the openings 35 as shown by Fig. 8, the downwardly depressed portion laying between re-enforcing ribs 22. The locking projections 34 are also provided with grooves or readily bendable portions 28 whereby said locking projections may be bent to the second semi-formed and finally formed positions without bodily deflection thereof.

Whereas the locking projections 34 have been shown as projecting inwardly in their semi-formed state, they may project outwardly as shown by a dotted form 34b, under which condition the openings 35 would be moved to the position as shown by the dotted lines 35b.

Auxiliary locking projections, as 29, may be stamped from the body of fingers 33 and in their initial semi-formed position are depressed slightly below the finger body to permit shearing of the metal for forming the same. As fingers 33 are bent to their second semi-formed position 33a, the locking projections 29 do not move and after the clamping member 30 has been applied to a binder or folder 27 said locking projections will enter the perforations 27 whereafter they are finally formed by bending downwardly and outwardly to the dotted position 29a as shown, the ends of said locking projections overlying the body of said binder or folder adjacent the perforations therein. Auxiliary locking projections as 29 may also be added to clamping member 20, or said projections may be solely employed for locking the clamping member to said binder or folder.

Furthermore self-piercing locking projections as 29a may be added to the ends of the base portion 21 of clamping member 20 and in their initially formed position, lay in a plane substantially parallel to the plane of the fingers 23 in their initially formed position 23a, said locking projections being reformed to a second semi-formed position parallel to the second semi-formed position 23a of fingers 23. Thereafter the clamping member is applied to the folder or binder and as the fingers 23 pass through the perforations 26, said locking projections will pierce said folder or binder adjacent the perforations whereafter they are bent downwardly inwardly or outwardly over the body of said binder or folder.

Similar locking projections 29b may be formed on the parallel edges of the base portion 21 and in their initially formed, reformed and finally formed position will act similarly to the locking projections 29a. Said locking projections 29a and 29b may also be employed jointly or solely with other locking projections disclosed herein

or in said copending applications or on any of the clamping members disclosed in said copending applications and said issued patent.

It is to be understood that the keeper 3 of Figs. 10 and 11 is formed with similar ends 6 at each end thereof thereby forming the rectangular opening 12 therein.

What I claim is:—

1. In a paper fastener, a clamping member 10 having fingers arranged to pass through perforated sheets of paper for the binding thereof, a keeper including a keeper plate having end portions connected by spaced rail portions forming a frame including a central opening therethrough 15 having a width wider than the width of the fingers, perforations in the end portions for receiving the fingers of the clamping member therethrough, the fingers being bent down into the central opening of the keeper plate for binding 20 the sheets, and locks slidable upon the rail portions arranged to be slid over the downwardly bent fingers for the locking thereof.
2. In a keeper for paper fasteners, a keeper plate having end portions connected by spaced rail portions whereby a central opening is formed therethrough, rectangular perforations in the end portions, a bridge portion on the end portions forming one edge of the rectangular perforations, the rail portions being positioned below the end 25 portions and the bridge portions being positioned below the rail portions, and locks slidable on the rail portions arranged to move over the bridge portions.
3. In a keeper for paper fasteners, a keeper plate having raised end portions connected by spaced rail portions whereby a central opening is formed therethrough, perforations in the end portions, a bridge portion on the end portion between the perforations and the central opening, the rail portions being positioned below the end 30 portions and the bridge portions being positioned below the rail portions, and locks slidable on the rail portions arranged to move over the bridge portions.
4. In a keeper for paper fasteners, a keeper plate having perforated end portions connected by spaced rail portions, the rail portions being positioned below the end portions with respect to the uppermost surfaces thereof, and locks 35 slidable on the rail portions the uppermost portion of the locks being substantially in the same plane as the uppermost portion of the end portions.
5. In a lock for paper fastener keepers, a rectangular bridge portion having shoe portions joined to one pair of parallel edges thereof, and trough portions formed inwardly of the other pair of parallel edges thereof.
6. In a clamping member for paper fasteners, 40 a base portion having fingers joined to each end thereof arranged to enter perforations in a binder for holding paper sheets therein, and semi-formed locking projections on the member inwardly adjacent the fingers for locking the member to the binder when finally formed, the semi-formed locking projections being arranged to enter the same perforations of the binder as entered by the fingers upon applying the clamping member to the binder.
7. In a clamping member for paper fasteners, 45 a base having fingers joined to each end thereof arranged to enter perforations in a binder for holding paper sheets, the fingers being initially semi-formed in a plane obliquely to the plane of the base for more economical packaging, and

semi-formed locking projections on the member for locking the member to the binder, the locking projections being also initially semi-formed in a plane obliquely to the plane of the base for more economical packaging.

8. In a clamping member for paper fasteners, 5 a base having fingers joined to each end thereof arranged to enter perforations in a binder for holding paper sheets, semi-formed locking projections on the base portion for locking the member to the binder, and openings in the base through which the semi-formed locking projections of other clamping members may enter when matingly assembling a number of the clamping members for packaging.

9. In a clamping member for paper fasteners, 10 a base having fingers joined to each end thereof arranged to enter perforations in a binder for holding paper sheets, and piercing locking projections on the base portion for locking the member to the binder, the locking projections being initially semi-formed obliquely to the plane of the base for economical packaging, then reformed to a second semi-formed position for piercing the binder and finally formed for locking the clamping member thereto.

10. In a clamping member for paper fasteners, 15 a base having fingers joined to each end thereof arranged to enter perforations in a binder for holding paper sheets, and semi-formed locking projections stamped from the body of the fingers for locking the member to the binder upon the final forming thereof, the locking projection being arranged to enter the same perforations of the binder as entered by the fingers when the clamping member is secured to the binder.

11. In a clamping member for paper fasteners, 20 a base having fingers joined to each end thereof arranged to enter perforations in a binder for holding paper sheets, and semi-formed locking projections stamped from the body of the base inwardly of the fingers for locking the member to the binder upon final forming thereof, the semi-formed locking projections being arranged to enter the same perforations of the binder as 25 entered by the fingers when the member is secured to the binder.

12. In a clamping member for paper fasteners, 30 a base having fingers joined to each end thereof arranged to enter perforations in a binder for holding paper sheets therein, semi-formed locking projections on the base arranged to pass through the body of the binder and be finally bent for securing the member thereto, and openings in the base into which the portion of the 35 binder body underlying the locking projections is constrained to enter, the area of the openings being greater than the area of the locking projections for preventing shearing of the binder body when the locking projections are bent to 40 final form.

13. In a clamping member for paper fasteners, 45 a base having fingers joined to each end thereof arranged to enter perforations in a binder for holding paper sheets therein, semi-formed locking projections on the base arranged to pass through the body of the binder and be finally bent for locking the member thereto, and readily bendable portions joining the base and the locking projections for permitting the bending of the locking 50 projections from semi to final form without deforming the body thereof.

14. In a clamping member for paper fasteners, 55 a base having fingers joined to each end thereof arranged to enter perforations in a binder for 60

holding paper sheets therein, and piercing locking projections joined to the ends of the base spacedly each side of the fingers arranged to pierce the body of the binder when the member is applied for locking the clamping member to the binder.

15. In a clamping member for paper fasteners, a base having fingers joined to each end thereof arranged to enter perforations in a binder for holding paper sheets therein, and semi-formed piercing locking projections joined to the ends of the base spacedly each side of the fingers arranged to pierce the binder body for locking the member thereto as they are finally formed when applying the member to the binder.

16. In a clamping member for paper fasteners, a base having fingers joined to each end thereof arranged to enter perforations in a binder for holding paper sheets therein, and semi-formed piercing locking projections joined to the parallel edges of the base spacedly between the ends thereof arranged to pierce the binder body for locking the member thereto as they are finally formed when applying the member to the binder.

17. In a clamping member for paper fasteners, a base having fingers joined to each end thereof arranged to enter perforations in a binder for holding paper sheets therein, the fingers having initially formed and reformed positions, and initially semi-formed piercing locking projections joined to the ends of the base portion arranged to pierce the binder body for locking the member thereto as they are finally formed when applying the member to the binder, the locking projections being initially semi-formed in a plane parallel to the plane of the fingers in their initial form.

18. In a clamping member for paper fasteners,

a base having fingers joined to each end thereof arranged to enter perforations in a binder for holding paper sheets therein, the fingers having initially formed and finally formed positions, and initially semi-formed locking projections joined to the parallel edges of the base spacedly between the ends thereof arranged to pierce the binder body for locking the member thereto as they are finally formed when applying the member to the binder, the locking projections being initially formed obliquely to the plane of the base for more ready packaging thereof.

19. In a clamping member for paper fasteners, a base having fingers joined to each end thereof arranged to enter perforations in a binder for holding paper sheets therein, semi-formed locking projections joined to the ends of the base spacedly each side of the fingers arranged to lock the member to the binder as they are finally formed when applying the member to the binder, and more readily bendable portions at the juncture of the locking projections and the base for permitting the bending of the locking projections from the semi to final form without deflecting the body thereof.

20. In a clamping member for paper fasteners, a base having fingers joined to each end thereof arranged to enter perforations in a binder for holding paper sheets, semi-formed locking projections stamped from the body of the fingers arranged to lock the member to the binder upon the final forming thereof, and more readily bendable portions joining the locking projections to the clamping member for permitting the bending of the projections from semi to final form without deforming the body thereof.

OSCAR A. ROSS.
